UNITED STATES PATENT OFFICE.

ALBERT KATZKE, OF MILWAUKIE, OREGON, ASSIGNOR OF ONE-HALF TO B. M. FISCH,
OF MILWAUKIE, OREGON.

EMERY-CLOTH FILE.

1,277,601.

Specification of Letters Patent. Patented Sept. 3, 1918.

Application filed May 4, 1916. Serial No. 95,363.

To all whom it may concern:

Be it known that I, ALBERT KATZKE, a citizen of the United States, residing in Milwaukie, county of Clackamas, and State 5 of Oregon, have invented certain new and useful Improvements in Emery-Cloth Files, of which the following is a specification.

My invention relates to emery cloth files, and more particularly to a simple, two-part 10 device adapted to receive strips of emery cloth, sand paper, or the like, and to hold them in stretched condition, whereby the device can be used as a file.

Among the salient objects of my invention are,—to provide a simple, cheap and practical two-part device, the parts of which are hinged together in a way which makes it possible to break the joint, and to attach the opposite ends of a strip of emery 15 cloth, or the like, to the outer ends of said parts, and then by closing them together to stretch the emery cloth lengthwise on the device; to provide in a device of the character referred to, two parts which can be 20 frictionally held together, with means for increasing, or diminishing, the friction therebetween, as desired; to provide a simple means in the ends of said parts, whereby said strips of emery cloth can be quickly 25 and effectively attached or detached and firmly held.

In order that others may understand my invention, I have illustrated one practical embodiment thereof in the accompanying 30 sheet of drawings, which I will now describe.

Figure 1 is a top plan view of a device embodying my invention;

Fig. 2 is an edge view thereof;

Fig. 3 is an edge view of the two parts, with their joint broken to loosen the emery cloth attached thereto;

Fig. 4 is a cross sectional view taken on line 4—4 of Fig. 2; and

Fig. 5 is a cross sectional view through a slightly modified form of the device having one round side and one square side.

Referring now more in detail to the drawings, my device comprises a two-part member, the parts of which are designated 1 and 2, hingedly secured together, as by means of a screw 3. The part 1, has its middle portion cut out longitudinally thereof to receive therebetween a portion 2^a, 55 of the part 2. The cuts made in the part

1, are extended, as at 1^a, and said part 1, is provided with a screw 4, whereby as said screw 4, is tightened, the two sides of the part 1 will be drawn together into closer frictional engagement with the middle part 2^a, of the part 2. The outer ends of the parts 1 and 2, are provided with transversely extending sockets 5 and 6, as clearly indicated in the edge views of Figs. 2 and 3, said sockets being larger at their inner ends than they are at their outer ends. A strip of emery cloth 7, is folded at its ends and inserted edgewise into the receiving sockets 5 and 6, while the parts are in the positions shown in Fig. 3. When said parts 1 and 2 are closed together, as in Figs. 1 and 2, it will be clear that the emery cloth 7, will be stretched lengthwise of the device. Said emery cloth can be placed on either side of the parts 1 and 2, so as to have either a flat base or a rounding base, as desired. When it is placed upon the rounded side of the members 1 and 2, said members are opened in the opposite direction from that indicated in Fig. 3, and the emery cloth attached as before described.

The parts 1 and 2 may be made in various forms, as for example, in Fig. 5, I have shown it of narrower construction, having a round side and a square side. In this figure, 8, designates the part corresponding to part 1 in the other form, and 9 designates the part corresponding to part 2 in said other form. The emery cloth 10, is shown as stretched along the rounded side of said device. This form of the device can be inserted in a round hole for smoothing the inside thereof, the emery cloth conforming readily to the form of the member upon which it is stretched.

While I have used the terms "emery cloth" and "sand paper," I wish it understood that any kind of smoothing or polishing strips can be attached to my device.

I do not limit my invention to the particular forms here shown for purposes of illustration, except as I may be limited by the hereto appended claims.

I claim:

1. A device of the character referred to, comprising a two-part member, the parts of which are arranged in overlapping relationship with each other and pivoted together intermediate the ends of each, in the same plane, to be moved apart transversely of the 110

plane occupied by the parts when closed together, said parts being of substantially the same thickness throughout, and a strip of emery cloth attached at its opposite ends 5 to the extreme opposite ends of said parts, substantially as described.

2. A device of the character shown and described, comprising in combination, a two-part member, one part of which has a middle longitudinal portion cut therefrom, and the other part of which has two side longitudinal portions cut therefrom, the middle portion of one part being pivotally secured between the side portions of the other part, and a 10 piece of emery cloth, having its opposite ends secured to the outer ends of said device, whereby as the parts of said device are closed together said emery cloth is stretched thereupon.

20 3. A device of the character shown and described, comprising in combination, a two-part member, one part of which has a middle longitudinal portion cut therefrom, and the other part of which has two side longitudinal portions cut therefrom, the middle portion of one part being pivotally secured between the side portions of the other part, a piece of emery cloth, having its opposite ends secured to the outer ends of said device, 25 whereby as the parts of said device are closed together said emery cloth is stretched thereupon, and means for increasing the frictional engagement of the interfitting portions of said device.

35 4. A device of the character shown and described, comprising a two-part member, one part of which has a middle, longitudinally extending portion thereof cut away,

and the other part of which has two side longitudinally extending portions thereof 40 cut away, the middle portion of one part being pivotally secured between the side portions of the other part, whereby said parts can be closed together in alinement with each other to form a uniform strip, 45 means for holding said parts together, said parts being provided on their outer ends with holding sockets adapted to receive the opposite ends of a strip of emery cloth, and a strip of emery cloth having its opposite 50 ends detachably secured in said holding sockets, substantially as described.

5. A device of the character referred to, comprising a two-part member, one part of which has two longitudinally extending side 55 portions, and the other part of which has a longitudinally extending middle portion pivotally connected between the side portions of said first part, said parts being adapted to be moved relative to each other 60 into and out of alinement, the outer ends of said parts being provided with holding sockets adapted to receive the opposite ends of a strip of emery cloth, and a strip of 65 emery cloth having its opposite ends attached to the outer ends of said members, whereby as said members are closed together they operate to stretch said emery cloth lengthwise thereupon.

Signed at Portland, Multnomah county, 70
Oregon, this 28th day of April, 1916.

ALBERT KATZKE.

In presence of—

I. M. GRIFFIN,
J. C. STRENG.
